DAM STRUCTURE

Eugenio Diaz del Castillo y Español,
Buenos Aires, ArgentinaApplication May 12, 1943, Serial No. 486,717
In Argentina March 20, 1943

3 Claims. (Cl. 61—30)

1

The present invention relates to dams and more particularly to dams composed of sections which are so arranged relative to one another and to the ground, as to prevent sliding and to reduce the quantity of building material required to restrain a water head of any given magnitude.

The gravity type dam, which may be defined as a dam which does not depend on arch action to resist the forces imposed upon it, while widely used, is subject to the disadvantage that to prevent sliding and bad distribution of the loads produced by the weight of the dam itself and the water restrained thereby, it is necessary to employ very large quantities of building material which render the completed structure unduly costly from the point of view of both labor time consumed and material used.

It is therefore an object of this invention to provide a dam which will mitigate the economic disadvantages of the known type gravity dam and which is characterized by a construction which is adaptable to solid construction, buttress construction, multiple arch construction, or the like.

Other objects and advantages of this invention will be apparent from the following detailed description of preferred embodiments thereof in conjunction with the annexed drawings wherein:

Figure 1 is a fragmentary plan view of a dam constructed in accordance with this invention, the view being limited to the portion of the dam which extends from the center line of the stream over one hillside;

Figure 2 is an elevational view showing the upstream face of the construction of Figure 1;

Figure 3 is a view in cross section taken along the line 3—3 of Figure 1, reference planes for certain mathematical considerations being rendered in chain lines;

Figure 4 is a perspective view of a modified type of dam constructed in accordance with this invention taken from a downstream direction; and

Figure 5 is a fragmentary view in perspective of a dam section illustrating the application of this invention to buttress construction.

Referring now in greater detail to the drawings and particularly to Figures 1 to 4 inclusive, it will be noted that the dam of this invention is composed of sections 10 which are in the over-all form of truncated prisms. It can be seen that if the sections 10 are set in position across the valley which is to be dammed in such relation to each other that angular open spaces 11 facing downstream are provided at each of a plurality of re-

2

entrant angles 12 on the upstream side. It can be seen that if the sections 10 are so disposed relative to one another as to define a dam crown line 13 of a broken character including line components 14, 15 and 16, each extending in a different direction, said line components being oblique in each case to the horizontal projection 17, Figure 1, of the lines 18 of maximum slope of the hillside, see Figure 2, a dam will be obtained consisting of a plurality of prisms 10 more or less truncated depending upon the ground contour. The direction of flow of the water of the stream or river to be dammed is shown by an arrow in Figure 1. It is noted that the dam axis line 13 extends in an upstream direction from the center line of the stream so that the bases of the sections 10, while having a general slope toward the center of the stream will, transversely to their axes, slope in the upstream direction.

20 To facilitate consideration of the foregoing, the angles and slopes that must be taken into consideration in the construction of a dam in accordance with this invention, have been set forth in Figures 1, 2 and 3 of the drawings. The angles β_1 , β_2 , β_3 and β_4 are defined between the slope of the ground at the particular point and the vertical. The angle α , see Figure 3, is the apex angle of the dam. η is the angle defined between the horizontal and the line of slope of the base of a section 10 transversely of its axis. θ and $\theta - \eta$ are dam sliding angles. The angles γ_1 , γ_2 , γ_3 , and γ_4 are defined between the horizontal projections 17 of the line 18 of maximum slope and the axis lines 14, 15 and 16 respectively of the dam sections. γ and η in Figures 4 and 5 refer to the same angles. The slope of the base 21 of each section 10 transversely of its axis results in a narrower base for the sections 10 since, in the absence of this slope, the cross section of the dam section at any point would be a right triangle, see the broken line 22 of Figure 3, while, with the slope, the angle between the wetted face of the section and the base thereof is always less than 90° . Hence, for 40 any given section apex angle α a narrower section results from the construction of this invention.

The narrowness of the section resulting from the inclination of the base transversely of its axis has the concomitant advantage that the height of the downstream face 23 of the section is reduced. The over-all gain in reduction in volume can be appreciated by comparing the full line cross section of Figure 3 with the broken line cross section which would result if the base of the section were not sloping transversely of its axis.

It is, of course, to be understood that the economy of material apparent from Figure 3 is somewhat reduced due to the fact that the over-all length of the dam of the present invention must somewhat exceed the over-all length of a conventional dam at the same site.

It is apparent that the construction of the present invention affords a high degree of stability against sliding due to the fact that the ground affords horizontal reactions in an upstream direction which contribute to resisting the thrust of the water.

At the bottom of the valley and in those zones of the hillsides in which the slope increases as the ground rises, it is apparent that the angles defined between the components of the line 13 will, in general, be reentrant on the upstream side and, between the sections which are in contact with each other at the wetted face, there will be angular open spaces at 14 facing in a downstream direction.

Of the spaces 11, the most important, although be it not always the largest, is the one at the bottom of the valley which affords economy in the most difficult and expensive part of the foundation. The joints between the sections 10 will be beveled and made watertight by any known means.

In those areas where the slope of the hillside diminishes, the angles of the axis line 13 will project outwardly in an upstream direction as indicated at 20 in Figure 1. There will be virtual superposition of the ends of the sections of the dam corresponding to a smaller resultant of the thrust of the water in these areas. These projecting angles at 20 can, of course, be replaced by curves. By selecting a correct axis line, bearing in mind the slopes of the hillsides in any particular case, it is possible to obtain a minimum over-all volume of building material whereby economies in construction are effected.

The selection of an axis line can be utilized not only as the basis for the construction of a dam of minimum structural volume, but also may be utilized for obtaining a greater inclination of the bases of the sections so as to achieve improved disposition of the stresses to which the dam is subjected or an improved stability against sliding. If, starting from the obliquity of the axis which is required for a dam of minimum structural volume, the axis obliquity, i. e.: the angle γ , is increased, one will eventually arrive at an axis obliquity where the greater over-all length of the dam is compensated for by the lesser cross sectional area of its component sections. If the obliquity of the axis line is continued beyond this point, the structural volume of the dam will continue to increase.

Referring again to Figure 3, it can be seen that the angle θ is the sliding angle which would exist if the base 21 of the section 10 did not slope transversely of its axis. In such a case the line representing the resolved forces acting on the

dam would lie at 24 and would define an angle θ with a line 25 lying at right angles to the assumed base 22. The actual sliding angle of the present dam is represented by $\theta - \eta$ and is defined between a line 26 representing the resolved forces acting on the dam and a line 27 at right angles to the base 21. It can be seen that $\theta - \eta$ is always smaller than θ since the tendency of θ to increase with the dam of the present invention is more than compensated for by the increase of η . Accordingly, the resistance to sliding of the present invention is great compared to a conventional dam. In solid dams, the division of the dams into sections with some open spaces between suppresses substantially all longitudinal reactions to the ground. There remains to be considered the longitudinal stresses which may arise from the pressure of the water on those surfaces of the dam which are in contact with the ground. The importance of this pressure is different from that of the subpressures because it is much easier to eliminate it by efficient drainage of the ground applied to surfaces of the terrain not loaded by the dam. The angular spaces arising in the construction of the dam of the present invention facilitate drainage. In buttress or multiple arch dams the ready elimination of longitudinal pressures is even more clearly seen.

It is apparent that the foregoing remarks apply not only to masonry dams or the like, which have a vertical or substantially vertical wetted face, but also to dams of the buttress type having a substantially inclined wetted face, see Figure 5. In the latter case, a further advantage results from the diminution of the weight of water required for stability. Compensation for this diminution is afforded by the inclination of the base of each section transversally of its axis, see angle η in Figure 5.

What is claimed is:

1. A dam structure having a broken line axis comprising a plurality of sections substantially in the over-all form of truncated prisms; the horizontal axes of said prisms being oblique to the horizontal projections of the line of maximum slope of the hillsides; the foundation base of each section being declivous, transversely to the section axis, toward upstream; whereby to afford foundation reactions opposite to water pressure, stability against sliding, reduced foundation width, and downstream reduction of height and accordingly diminution of the stresses; said sections being set in angular relationship with each other, defining between them at the reentrant upstream angles of the dam angular open spaces facing downstream, providing for drainage and free contraction; and impervious joints at the upstream contact of these sections.

2. A dam as claimed in claim 1 having solid sections.

3. A dam as claimed in claim 1 having sections of the buttress type.

EUGENIO DIAZ DEL CASTILLO Y ESPAÑOL.
